PENCIL SHARPENER

Ronald B. Rosson, Roslyn Estates, N.Y. (½ ADI, Inc.,
1535 Decatur St., Ridgewood, Brooklyn, N.Y. 11221)

Filed Nov. 5, 1971, Ser. No. 196,262

Term of patent 7 years

Int. Cl. D19—99

U.S. Cl. D74—21 B

Fig. 1.

Fig. 2.

Fig. 3.

Fig. 4.

Fig. 5.

Fig. 6.

FIG. 1 is a front, side and top perspective view of my pencil sharpener embodying the features of my new design;

FIG. 2 is a top plan view thereof on smaller scale;
FIG. 3 is a front elevational thereof;

FIG. 4 is a rear elevational view thereof;

FIG. 5 is a side elevational view thereof, the view being taken as looking towards the left of FIG. 1;

FIG. 6 is a bottom plan view.

I claim:

The ornamental design for a pencil sharpener, substantially as shown.
